UNITED STATES PATENT OFFICE.

WILLIAM F. KASBOHM, OF VAN WERT, OHIO.

SECTIONAL CASING FOR FURNACES.

1,350,257.

Specification of Letters Patent. Patented Aug. 17, 1920.

Application filed February 16, 1916. Serial No. 78,655.

To all whom it may concern:

Be it known that I, WILLIAM F. KASBOHM, a citizen of the United States, residing at Van Wert, in the county of Van Wert and State of Ohio, have invented certain new and useful Improvements in Sectional Casings for Furnaces, and I do hereby declare the following to be a full, clear, and exact description of the invention, such as will enable others skilled in the art to which it appertains to make and use the same.

This invention relates to new and useful improvements in sectional casings for furnaces and the principal object of the invention is to provide a device which may readily be assembled or disassembled without the necessity of using screws or bolts.

Another object of the invention is to provide a device which will permit one of the sections to be removed so that any repairs may be made to the furnace without the necessity of taking down the entire structure.

With these and other objects in view, the invention consists in the novel combination and arrangement of parts which will be fully set forth in the following specification and accompanying drawings, in which:

Figure 1 is a view in elevation illustrating the assembled furnace casing.

Fig. 2 is a top plan view of Fig. 1 showing the floor boards removed.

Fig. 3 is a sectional view on line 3—3 of Fig. 1.

Fig. 4 is a vertical sectional view on the line 4—4 of Fig. 1.

Fig. 5 is an enlarged fragmentary elevational view of the casing illustrating in detail one of the clasps.

Fig. 6 is a transverse sectional view of Fig. 5, and

Fig. 7 is a detail perspective view of one of the clasps.

Referring to the drawings, the numeral 1 designates as an entirety, the hood or bonnet of the device comprising the cylindrical shell 2 having the top or cover 3. Suitable hooks 4 are secured to the bonnet and connected to these hooks are chains 5, the use of which will appear as the description proceeds.

Formed in the bonnet are a plurality of openings 6^a to which the conductor pipes 55 are connected which distribute the warm air

throughout the building in which the device is used.

The upper ends of the chains 5 are connected to suitable hooks 6 which are pivoted as at 7 to a stationary support such as the floor joists shown in Fig. 1. The hooks are provided with the levers 8 by means of which the same may be swung into the dotted line position shown in Fig. 1 so that the bonnet may be lifted from the remaining portion of the casing to enable the casing and furnace to be removed without wholly removing the distributing and conducting pipes. It is intended, in practice, to have the hooks 6 of such length that, when they are rocked into the dotted line position shown in Fig. 1, the hood will be lifted sufficiently to permit bodily removal of the furnace from beneath this hood after the body of the casing surrounding the furnace has been removed. When it is not desired to remove the furnace the hood need not be lifted, as access to the interior of the casing may be readily obtained by removing one or more of the detachable sections thereof, as will be readily understood. In this case, any or all of the sections of the body of the casing may be removed independently of the hood which is suspended by the chains 5.

The body of the furnace casing is designated by the numeral 9 and comprises a plurality of arcuate plates 10, each of which is provided at one of its vertical edges with a suitable pocket 11 formed by bending the metal back upon itself as at 12 and then off setting the edge outwardly and in parallel relation as at 13 to form a cover flange for engaging the edge of the adjacent section. This construction is clearly shown in Fig. 3 and it will thus be seen that a dust proof joint is formed between the vertical edges of the adjacent sections.

In order that the adjacent edges may be held against separation, a suitable clasp is provided which comprises a loop 14 in which is pivotally mounted the ends of the arms of a substantially V-shaped frame 15 forming the body of the clasp. The locking lever of the clasp is designated generally by the numeral 16 and comprises a substantially V-shaped frame 17 the ends of the arms of which converge and are looped as at 18 around the bight portion of the V-shaped frame 15 and are extended to form the tongue 19 the end of which engages the

pocket of the adjacent section to hold the same in place.

In order that the upper and lower edges of the sections may be properly held in position, a suitable transverse ring 20 is provided and is adapted to fit within the sections and each section is provided near this ring with suitable openings 21 in which the pins 22 are mounted. These pins are provided at their outer ends with the heads 23 having suitable handles 24 connected thereto while the inner ends of the pins are formed with hooks 25 for engaging the inner face of the ring.

It will be understood that the sections may be provided with suitable door openings if so desired to enable the user to gain easy access to the fire box and ash pit of the furnace as in the ordinary manner.

It will be apparent from the foregoing that in use the device is assembled in the manner illustrated in Fig. 1, and if it is desired to gain access to the interior of the casing, it will be evident that by releasing the clamps on the vertical edges of the section and the turning of the handles 24 so as to release the hooks 25 from the ring, the sections may be removed and any repairs may be made to the furnace. In case one of the sections should be injured, it will be readily seen that the same may be removed and a new section substituted therefor without necessitating the taking down of the entire device.

It will also be seen that when so desired the furnace may be entirely removed without disturbing the piping by lifting the hood 1 by the movement of the levers 8 and after the same has been replaced, it will be evident that the hood may be returned to its original position by moving the levers to the position shown in the full lines in Fig. 1.

While in the foregoing there has been shown and described the preferred embodiment

of this invention, it is to be understood that such changes may be made in the combination and arrangement of parts as will fall within the spirit and scope of the appended claims.

What is claimed is:—

1. The combination with a furnace casing comprising a body consisting of a plurality of independently removable sections, and a removable hood for said body, of means for elevating and suspending the hood so as to permit said sections of the body to be removed independently of said hood.

2. The combination with a furnace casing comprising a body consisting of a plurality of independently removable sections and a removable hood, of means independent of said body for elevating and suspending the hood so as to permit said sections of the body to be removed independently of said hood.

3. The combination with a furnace casing comprising a sectional body, a hood, and means detachably connecting the sections to each other and to the hood, of means for elevating and suspending the hood independently of the body so as to permit independent removal of said sections.

4. The combination with a furnace casing comprising a body consisting of a plurality of independently removable sections, and a removable hood, of means for elevating and suspending said hood independently of the body so as to permit independent removal of said sections of the body, said means being adapted to elevate the hood for permitting bodily removal of a furnace positioned beneath the same.

In testimony whereof I affix my signature in presence of two witnesses.

WILLIAM F. KASBOHM.
